UNITED STATES PATENT OFFICE.

CHARLES MUNZNER, OF CHICAGO, ILLINOIS, ASSIGNOR TO AMERICAN STOVE COMPANY, OF ST. LOUIS, MISSOURI, A CORPORATION OF NEW JERSEY.

DEMONSTRATING OR ADVERTISING DEVICE.

Application filed April 30, 1923. Serial No. 635,759.

To all whom it may concern:

Be it known that I, CHARLES MUNZNER, a citizen of the United States, residing at Chicago, in the county of Cook and State of Illinois, have invented certain new and useful Improvements in a Demonstrating or Advertising Device, of which the following is a specification, reference being had thereto in the accompanying drawing.

This invention relates to improvements in a demonstrating or advertising device, for an oven heat regulator.

My improved device is designed and constructed primarily for advertising and demonstrating the operation and efficiency of the "Lorain" oven heat regulator, which regulator is patented and works on the thermostat principle.

Although I have stated that my device is for demonstrating a "Lorain" oven heat regulator, I wish it to be understood that the same could be utilized with regulators of other forms without departing materially from the scope of my invention.

The particular embodiment of the invention in the drawing is adapted for use for thermostatic regulators, such as shown in the following B. E. Meacham Patents Nos. 1,236,335, August 7th, 1917; 1,334,776, March 23rd, 1920; 1,339,964, May 11th, 1920, and other improved patented structures of the same patentee, which it is not thought necessary to enumerate.

The object of this invention is to provide a demonstrating device for temperature controlling regulators.

Another object of the invention is to provide a device for demonstrating the operation of the "Lorain" oven heat regulator.

A further object of the invention is to provide an automatic demonstrator for temperature controlling regulators.

Other objects and improved results of my invention will appear in the following description and accompanying drawings.

In the drawings:—

Figure 1 is a perspective view of my improved demonstrating device, the doors of the device being shown in open position.

Fig. 2 is a vertical sectional view of the device, the doors being shown in a closed position in full line and in an open position in dotted lines.

Fig. 3 is an end view of my improved de-

vice showing a modified form with the automatic motor-driven door operating means.

Fig. 4 is a rear view of the automatic door-operating mechanism, showing its operative connection with the doors of the device.

Fig. 5 is an end view of my improved device showing the thermostatic control and the cards carrying the descriptive matter, the rear door of the device being shown in dotted line.

Referring now to the drawings in which like parts are designated by similar reference numerals throughout the description, A represents a narrow, preferably metal, box having closed sides 5, and a closed top 6 and bottom 7. The front of the box has a closed window 8 across its bottom above which is pivotally mounted, as at 9, in the closed sides 5, a door 10, adapted to swing inwardly, as clearly appears in Figs. 1 and 2 of the drawings.

The back of the box is closed across its bottom by a rear wall 11, above which is pivotally mounted in the side walls 5, as at 12, a door 13, which is adapted to swing outwardly as clearly appears in Figs. 1 and 2 of the drawings.

Suitably supported within the bottom of the metal box A is a gas-burner 14, so positioned as to be visible from the outside of the box through the front window 8. One end of the burner 14 is connected in the usual manner to the regulator B, which receives a supply of gas through any ordinary connection.

Ordinarily, the regulator would be enclosed in a metal housing, but to make the operation of the regulator visible, I have enclosed the working parts with a glass housing designated at 15. The regulator is provided with a temperature wheel 16, which is common to devices of this character.

The front and rear doors 10 and 13 of the device are connected one to the other by a suitable rod 17, or the like, so that they will swing in unison and in the form of device shown in Figs. 1 and 2, the rear door is provided with a handle 18, for opening and closing the doors.

As clearly appears in Figs. 2 and 3 of the drawings, the rear door 13 of the box A, does not reach entirely to the top of the box. Above the door is an upper rear wall 19 upon which is supported a vertical stand-

ard 20, by a suitable bracket 21, in such a manner that the upright can be revolved. The lower end of the upright is provided with an outwardly projecting pin 22, which 5 engages the slot 23 of the link 24, which is supported upon the bracket 25, carried by the upper edge of the rear door 13.

The vertical upright 20 is provided at a point 26, which is above the box top, with a 10 plurality of radial arms 27, adapted to receive and support cards or signs 28, upon which will be printed suitable reading matter to describe the operation of the device.

15 Operation.

The operation of the form of device, as shown in Figs. 1 and 2, is as follows:

The regulator B having previously been attached to a gas supply, the gas is turned 20 on and the burner 4 lighted. The doors of the devices are then closed and the interior of the box allowed to heat. The regulator wheel 16 is then set to any of the marked 25 temperatures on the wheel. When the heat within the box has reached the degree of heat at which the regulator wheel is set, the regulator will function and reduce the gas supply so that the burner will only burn sufficiently high to maintain the heat within 30 the box at the set temperature of the regulator wheel.

The operation of the regulator and the reducing of the flame of the burner will be apparent through the glass window 8 of the 35 box and the glass housing 15 of the regulator.

When the regulator has functioned to reduce the flame of the burner, the doors of the box are opened so that the interior of 40 the box, which is in reality an oven, can cool. The regulator wheel has not been moved so that as soon as the interior of the oven cools to a degree of heat less than that 45 at which the regulator wheel is set, the regulator will operate to increase the gas supply and this increase will become apparent as the flame at the burner 14 will enlarge.

When this second operation has taken 50 place, the doors of the oven will be closed and the operation as described will again occur.

It will be readily apparent that an indefinite number of the two operations, just described, can be carried on by merely opening and closing the oven doors. During the 55 operations of the regulator, it will be seen that as the doors are opened, the link 24 of the rear door is carried outwardly and that when the pin 22 of the vertical upright 20 engages the end of the segment slot 23, the upright will be revolved ninety degrees. It 60 will also be apparent when the doors are closed, that the upright will be again revolved when its pin 22 engages the opposite end of the link slot 23. The difference in

form of the links shown in Figures 2 and 3 is of no material importance and the use of either is optional.

The cards and signs carried by the radial arms 27 of the upright will carry wording 70 to describe the regulator operations. For instance, when the doors are open the two signs facing the front of the oven might carry suitable wording, such as "Open door cools the oven," "Regulator increases size 75 of the flame," and when the doors are closed, the sign might carry suitable words, such as "Closed doors heat the oven," "Regulator decreases the size of the flame."

Coming now to the modified form of the 80 device, as described in Figs. 3 and 4 of the drawing, it will be seen that the box A has the same top 6 and bottom 7, and front glass window 8, and rear door 13. In this form, I have done away with the front door 85 10 and have made the upper part of the oven front solid as at 30.

The oven is provided with the same upright 20 and supported in a similar manner as at 21, and having in its lower end the 90 opening 22. The rear door 13 carries the same bracket 25, which in turn carries the segment 24, having the slot 23, although the link 24 is of a slightly different shape and slightly shorter than the segment shown in 95 the other form of the device. The segment is shortened for the reason that in this form the rear door does not swing outwardly quite as far as in the other form of oven.

In place of the handle 18 on the rear door, 100 I have provided an outwardly extending arm 31, which pivotally engages, as at 32, the upper end of a bell-crank 33, which is pivotally supported at 34 upon a vertical standard 35. The opposite end of the bell-crank 33 is slotted, as at 36, and this slot engages a pin 37, carried concentrically upon the face of the wheel 38, which is driven through the gears 39, 40 and 41 of an electrical motor 42. As the electrical 110 motor is in close proximity to the heat of the oven A, it has been deemed advisable to provide a fan 43 for cooling the motor.

From the foregoing it will be readily apparent that the electrical motor will periodically open and close the rear door 13 of the oven or box and as the door is opened and closed the vertical upright 20 will be revolved and the different cards supported upon the upright will be shown to the front 120 of the oven.

It will also be readily seen that through the operation of the pin 37 in the elongated slot 36 of the bell-crank lever, 33, and due to the gearing 39, 40 and 41, the opening and 125 closing of the door can be timed to allow between the movement of the door the functioning of the oven regulator, which has been heretofore described. No attempt is made to describe the particular size of the 130

gears or the speed of the motor to accomplish the proper timing of opening and closing the door. The various elements entering into the timing would have to be regulated by the conditions, namely the size of the burner and the size of the oven. A variation in the size of either would affect the conditions so that no standard speed for driving the gears can be given. A simple manner for setting the timing would be to have a rheostat in the electric line to the motor so that the speed of the motor can be varied and controlled as the use of the device under its operating conditions would dictate. A device such as shown in Figs. 3 and 4 of the drawing, could be put in a store window and would automatically operate throughout a definite period and would fully and advantageously demonstrate the oven heat regulator.

A device such as is shown in Figs. 1 and 2, of the drawings, which is hand-operated, would necessitate the presence of an attendant to open and close the doors between the operations of the regulator.

I wish it to be understood that although I have shown and described a box form of device for demonstrating the operations of a heat regulator, that I do not restrict myself to this particular form, as devices for a similar purpose could be made in a different manner and still be within the scope of my invention.

Having thus described my invention, what I claim and desire to secure by Letters Patent is—

1. A demonstrating or advertising device for fuel regulators or the like, comprising a housing having a burner therein, a fuel regulator for the burner, and means to automatically periodically cool the housing.

2. A demonstrating or advertising device for fuel regulators, comprising a housing having a burner therein visible from the outside, a fuel regulator for the burner, and means to automatically periodically cool the housing, for the purpose described.

3. A demonstrator or advertising device for fuel regulators, comprising a housing having a burner therein, a fuel regulator for the burner, means to automatically periodically cool the housing, and the fuel regulator enclosed within a glass housing, for the purpose described.

4. A demonstrating or advertising device for fuel regulators, comprising a housing having a burner therein, a fuel regulator for the burner, means to automatically periodically cool the housing, and the operation of the burner and of the moving parts of the fuel regulator visible, for the purpose described.

5. A demonstrating or advertising device

for fuel regulators, comprising a housing having a burner therein, a fuel regulator for the burner, descriptive reading matter of the device operatively connected therewith, whereby the reading matter is periodically changed, and means to periodically cool the housing, for the purpose described.

6. A demonstrating or advertising device for a thermostatic fuel regulator, comprising a housing having a gas burner therein, a thermostatic regulator for the burner, and means to automatically cool the housing periodically, whereby the thermostat will periodically operate.

7. A demonstrating or advertising device for fuel regulators, comprising a housing, a burner therein, a fuel regulator for the burner, and an automatic means for periodically cooling the housing, whereby the regulator is caused to periodically operate, for the purpose described.

8. A demonstrating or advertising device for fuel regulators, comprising a housing having a burner therein, a fuel regulator for the burner, means for periodically cooling the housing to cause the regulator to operate periodically, and a movable support adapted to carry descriptive reading matter of the regulator operation operatively connected to the device, whereby the reading matter changes periodically with the operation of the regulator.

9. A demonstrating or advertising device for a fuel regulator, comprising a housing having a gas burner therein, a door for the housing, a fuel regulator for the burner, and means to open the housing door to automatically periodically cool the interior of the same for the purpose of causing the regulator to operate.

10. A demonstrating or advertising device for a fuel regulator, comprising a housing having a burner therein, a fuel regulator for the burner, a door for the housing, a support adapted to carry card signs or the like, said support in operative connection with the door, whereby the opening and closing of the door moves the support to change the position of the cards, and said door being the means for allowing the interior of the housing to cool, for the purpose described.

11. A demonstrating or advertising device for fuel regulators, comprising a housing having a burner therein, a door for the housing, a fuel regulator for the burner, and power driven means in operative connection with the door to periodically open the same, for the purpose described.

In testimony whereof I hereunto affix my signature.

CHARLES MUNZNER.
